Inventor:

*Franklin R. White,
By Parker, Cott, Atty.*

UNITED STATES PATENT OFFICE

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT

BUTTON

Application filed December 31, 1930. Serial No. 505,893.

My invention relates to new and useful improvements in buttons, and more particularly to a solid head button which may be formed preferably from a slug of soft steel or other 5 metal cut from rod stock and then pressed into shape by the action of one or more set of dies, and the same is a companion to an application filed herewith of even date and bearing Serial Number 505,894.

- 10 Another object of the invention is to form a solid head button preferably of non-tarnishing soft steel or steel alloy, the button being shaped by the action of suitable dies, after which a small disk of one of two forms will be 15 placed into a receptive recess and the lower edge of the steel button crimped or pressed over the disk, so that a tack or staple fastener may be driven into the disk to thereby attach the button to the cloth.
- 20 Still another object of the invention is to provide a two-piece button, which is known as the imperforate type, that is, wherein the tack or staple fastener is driven bodily through the metal disk situated in the hub of 25 the button, the center recess of the hub acting as an anvil to deform the tack or staple, so that the button when attached will be held rigidly to the cloth.

As is well known, these forms of buttons are 30 secured in place by attaching machines, that is, the button heads are fed from one hopper while the tacks or staples are fed from another hopper and the action so synchronized that the tack or staple will be driven up 35 through the cloth and into the button head to thus secure the button in place.

With these and other objects in view, the invention consists in certain new and novel arrangements and combinations of parts as 40 will be hereinafter more fully described and pointed out in the claims.

Referring now to the drawings showing one preferred form and one modification.

Fig. 1 is a sectional view of the button head 45 and, of course, on an enlarged scale;

Fig. 2 is a side elevation of the same partly in section and showing the disk member crimped within the hub;

Fig. 3 is a bottom plan view of the same;

50 Fig. 4 is a view similar to Fig. 2, the but-

ton, however, being inverted and a tack fastener driven up into the hub of the button to hold the button in place;

Fig. 5 is a view similar to Fig. 1, the button head being similar to Fig. 1, but with a larger central chamber;

Fig. 6 is a view similar to Fig. 2, showing an imperforate disk for receiving a staple instead of a tack;

Fig. 7 is a view similar to Fig. 3;

Fig. 8 is a view similar to Fig. 4, but showing the staple in place rather than the tack.

Referring now more particularly to the several views, there is shown in Fig. 1 a button head comprising what I term the top portion 65 1 and the hub 2 in which there is a small central chamber 3 with a recess 4 at one end thereof to form an inner shoulder 5 which, of course, extends completely around the inner wall of the hub.

As previously mentioned, this button head may be formed from rod stock and preferably of a relatively soft non-tarnishable steel, the rod stock being first cut into slugs of sufficient length. It may take one or more operations in a press with suitably formed dies but an automatic press (not shown) may have successive dies for forming the button head into the shape shown.

Now placed within the recess 4 and resting on the shoulder 5 may be seen a small hard metal disk 6 which is preferably depressed centrally, as at 7. The outer edge of the hub of the button 8 is then crimped or pressed over the adjacent peripheral edge 85 of the disk 6 to thus tightly secure the disk in place. The button head is now complete and, as may be seen, is exceedingly simple, it comprising merely a solid button head with its integral hub and chamber and its little disk crimped into place.

To secure the button to a cloth 9, as shown in Fig. 4, a tack 10 will have its prong 11 driven through the cloth and through the small disk 6 at its center 7. The prong or bill impinging against the upper wall of the chamber 3 will deflect and deform the prong, so that it will jam down against the inner surface of the disk, as may be readily seen.

Thus, the button will be tightly secured 100

in place and in ordinary usage it will be impossible to pull the tack from the button.

Very often, it is desired to use a staple button rather than a tack button (as they are termed in the art) and in this instance a button head 12 similar to the button head shown in Fig. 1 is used with the exception that the central chamber 13 is somewhat larger in diameter. In a recess 14 is placed a disk 15 but instead of having the disk depressed centrally it will be noticed that in this instance it is slightly domed, as at 16, and a small depressed annulus or ring 17 formed about the dome. The lower edge of the button 18 is then crimped over this disk in the same manner as the preferred form, shown in Fig. 2.

To secure this button to the cloth, a staple 19 is driven through the disk 15 and the annulus or ring 17 will tend to center the prongs 20 of the staple, so that they will, when driven into the hub, strike the wall of the chamber 13 and be deformed and deflected to thus tightly crimp the button in place.

From the foregoing, it will be seen that I have produced a button that is relatively cheap to manufacture, it comprising but the two parts. In the one instance, the central disk is depressed to center a tack fastener 30 and in the other instance there is a dome disk to center the prongs of the staple fastener.

It will also be understood that I have shown the outer surface of the button as plain but any desired insignia might be pressed in the same if called for by the trade.

Many slight changes may be made without in any way departing from the spirit and scope of the invention.

Having thus described my invention, what I claim as new and desire to secure by Letters Patent is:

1. A solid head button having an integral hub and a central chamber formed therein, a recess formed in the hub about said chamber to thereby form a shoulder, an imperforate disk fitting within the recess, the edge of the hub forced over said disk to hold the same tightly in place, and said disk provided with slanting walls centrally located and adapted to properly position a fastener to be driven through said disk.

2. A solid head button comprising an integral head and hub, said hub provided with a central chamber, a recess adjacent said chamber to form a shoulder, an imperforate disk having a dome center and a resultant ring about said dome, the said ring adapted to position the prongs of a staple and the walls of the chamber adapted to deflect the said prongs to hold the button head in position when the staple is driven in the button head.

In testimony whereof I affix my signature.
FRANKLIN R. WHITE.
